UNITED STATES PATENT OFFICE.

CHARLES F. RITCHEL, OF BRIDGEPORT, CONNECTICUT, ASSIGNOR TO JOHN STON, TALLMAN & CO., OF NEW YORK, N. Y.

TOY MOTOR.

SPECIFICATION forming part of Letters Patent No. 352,068, dated November 2, 1886.

Application filed May 6, 1886. Serial No. 201,281. (No model.)

To all whom it may concern:

Be it known that I, CHARLES F. RITCHEL, a citizen of the United States, residing at Bridgeport, in the county of Fairfield and State of Connecticut, have invented new and useful Improvements in Toy Motors, of which the following is a specification.

My invention consists of improvements in the contrivances of spring-motive power for toy carriages, having for its object to provide efficient durable machines having long range of operation for each setting, and at the same time being simple and cheap to construct, all as hereinafter fully described, reference being made to the accompanying drawings, in which—

Figure 1 is a longitudinal sectional elevation of my improved toy-motor carriage. Fig. 2 is a side elevation of one of the frame-bars of the motive apparatus. Fig. 3 is a plan of the motive apparatus inverted. Fig. 4 is a detail of the roller-ratchet of the driving-gear. Fig. 5 is a section on the line $x-x$ of Fig. 1.

The motive apparatus consists of the clock-spring contrivance having the coiled spring a , master-wheel b , one or more intermediate pinions, c , and wheels d , and the pinion e on the driving-axle f , the spring being fastened at its inner end to the fixed shaft g , and at its outer end to the master-wheel b .

My invention consists, first, in the contrivance of the bearing-frame for simplicity in the mounting of the pivots of the motive train, and for attachment of said frame to the carriage; second, in the contrivance for mounting the axle-driving pinion; and, third, in the winding-up clutch, as follows:

I make said frame of two (preferably cast, but they may be stamped) plates, h , having right-angle ends, i , terminating in perforated ears j , parallel to the plates, and serving to connect said plates together by a rivet through each pair, parallel to each other and at the required distance apart to form a rectangular frame. For the rivets to connect the plates I use eyelets z , for the greater ease of heading them in the fragile plates of the frame, which would be liable to break in the more severe work of heading solid rivets. These frame-plates have the pivot-bearings k for the driving-axle f ; also, bearings l for the intermediate

wheel, d , and pinion c , and also bearings m for the shaft of the master-wheel, all arranged so that the axles or pivots enter the bearings when the frame-plates are placed together, and are secured in their places when the frame is fastened together at the ends. The master-wheel shaft is then riveted; or it may be fitted in square holes to prevent turning when the spring, which is hooked onto it at n , is wound up. This makes a very simple contrivance for mounting the working-gears, and an equally simple contrivance for mounting the frame in and securing it to the bed-plate o of the machine, and also for the mounting of the master-wheel and spring, which, owing to the size it is desired to make them, have to be too large to be set under the bed-plate, where it is desirable to set the driving-axle, and also the intermediate wheel that carries the winding-post. I make said frame-bars with a vertical offset at p equal, or thereabout, to the vertical breadth of said bars; also, with the flanges q on the lower edges of the higher parts, and also with the attaching-lugs s on the upper edge of the lower parts of said bars, so that with a slot or opening through the bed-plate of length and breadth corresponding to the dimensions of the frame, except the connecting ear lugs and flanges, the frame, with the machinery attached, is readily applied to the bed-plate by inserting the connecting-lugs of the higher or front end of the frame through the slot from below, and letting them bear on the upper surface of the bed-plate at the end of the slot and bringing the flanges q and the lugs s up against the lower surface of said plate, and the securing of the frame is effectually accomplished by simply bending the clip-tongues t previously cut in the bed-plate around the lugs s to hold them up against the bed-plate, and also, in conjunction with the ear-lugs of the front end of the frame resting on the upper surface of the bed-plate, to hold flanges q up to said bed-plate.

I propose to dispense with the ordinary ratchet-wheel and click-pawl used to connect the spring and master-wheel, so that the spring may be wound up without turning the machine backward, both for the purpose of substituting a less expensive and more durable clutch, and also for so locating the clutch that the

pivot of the intermediate wheel and pinion may be used for the connection of the winding-key for the benefit of the easier winding which the leverage of the pinion and master-wheel affords.

The clutch which I use, and which I locate on the axle *f*, consists of the plain rollers *u* in the notches *v* of the pinion *e*, with the washer *w* on the axle at one side of the pinion to act in conjunction with the frame-bars *h* at the other side of said pinion to keep the rollers in the notches, which notches are slightly eccentric at the back to the axis, and so formed that when the spring is driving forward the rollers will be pinched on the axle in the smaller radii of the notches, and will be slackened off in the larger radii when the gear is turned the other way for winding. By the construction of the pinion with these notches extending entirely through it, so that the teeth, the hole, and the notches may all be punched in one operation, the wheel may be made in the simplest manner, and by the combination of the washer with the frame-bar for keeping the clutch-rolls in position a much simpler and cheaper means is provided for the purpose than that heretofore made.

For the connection of the winding-key *x* with the winding-post, so that the machine may not be carelessly turned back to the damage of the spring, I use a socket-key that will turn on the post and a common rose-clutch, *y*, formed, respectively, on the end of the socket and the hub of the winding-post.

What I claim, and desire to secure by Letters Patent, is—

1. The combination, with the bed-plate having the slot and clip-tongues, of the frame for the motor-pivots, composed of the plates having angular end flanges and terminal parallel riveting-ears, also side flanges and connecting-lugs, which side flanges are secured against the lower surface of the bed-plate by the clip-tongues bent around said connecting-lugs, the ear-flanges of the front end of the frame being

secured on the upper surface of said bed-plate, substantially as described.

2. The frame for the motor-pivots, composed of the plates having angular end flanges with terminal parallel riveting-ears, also side flanges and connecting-lugs for securing it to the bed-plate, and also pivot-ears for the pivots and hind axle of the motor-train, in combination with the bed-plate having the slot and clip-tongues, said side flanges and connecting-lugs being secured against the lower surface of the bed-plate by the clip-tongues of said plate bent around the connecting-lugs, the ear-flanges of the front end of the frame being secured on the upper surface of said plate, and the spring and master-wheel pivots located above and the pivots of the winding-up post and the driving-axle below the plane of said flanges, and connecting-lugs, substantially as described.

3. In a spring-power-driving mechanism for driving toy-carriages, the combination, with the transmitting-gear train and the carriage-axle, of the loose pinion on the axle gearing with said train, and having the eccentric roller-notches extending through the hub, the plane rollers located in said notches, the loose washer located on said axle, and the side plates of the frame, all constructed and arranged substantially as described.

4. In a spring-power-driving mechanism for carriages, the spring connected positively with the stationary pivot of the master-wheel, and also positively connected with said wheel, in combination with the transmitting gear train having the winding-post arranged intermediately in the train to the master-wheel and the disconnecting-clutch, and with said clutch located intermediately to the winding-post and axle or other shaft to be drawn, substantially as described.

CHARLES F. RITCHEL.
